PAPER REGISTRATION GUIDE FOR AN ELECTROPHOTOGRAPHIC COPYING MACHINE

Clyde R. Mayo, Brighton, N. Y., assignor to The
Haloid Company, Rochester, N. Y., a corpora-
tion of New York

Application December 8, 1950, Serial No. 13,334

Term of patent 14 years

(Cl. D64—11)

To all whom it may concern:

Be it known that I, Clyde R. Mayo, a citizen of the United States of America, residing at Brighton, in the county of Monroe and State of New York, have invented a new, original, and ornamental Design for Paper Registration Guide for an Electrophotographic Copying Machine, of which the following is a specification, reference being had to the accompanying drawings forming a part thereof.

In the drawings:

Fig. 1 is a top plan view of a paper registration guide for an electrophotographic copying machine, showing my new design;

Fig. 2 is a view in elevation looking from below upwardly with reference to Fig. 1;

Fig. 3 is a bottom plan view;

Fig. 4 is a view in elevation looking from above downwardly with reference to Fig. 1;

Fig. 5 is a transverse sectional view on the line 5—5 of Fig. 1; and

Fig. 6 is a view in end elevation.

I claim:

The ornamental design for a paper registration guide for an electrophotographic copying machine, as shown.

CLYDE R. MAYO.
